US00D835976S

(12) **United States Design Patent** (10) Patent No.: **US D835,976 S**
(45) Date of Patent: **** Dec. 18, 2018**

(54) **COUPLING MEMBER**(71) Applicant: **Boa Technology Inc.**, Denver, CO (US)(72) Inventors: **Michael Nickel**, Golden, CO (US);
Thomas Pollack, Denver, CO (US)(73) Assignee: **Boa Technology Inc.**, Denver, CO (US)(***) Term: **14 Years**(21) Appl. No.: **29/479,514**(22) Filed: **Jan. 16, 2014**(51) LOC (11) Cl. **08-08**

(52) U.S. Cl.

U.S. Appl. No. 09/956,601, filed Sep. 18, 2001, Hammerslag.

(Continued)

Primary Examiner — Sandra S Snapp*Assistant Examiner* — Ieisha N Price(74) *Attorney, Agent, or Firm* — Kilpatrick Townsend & Stockton, LLP(57) **CLAIM**

The ornamental design for a coupling member, as shown and described.

DESCRIPTION

FIG. 1 is a perspective view of the coupling member;

FIG. 2 is a bottom perspective view of FIG. 1;

FIG. 3 is a top plan view of FIG. 1;

FIG. 4 is a bottom plan view of FIG. 1;

FIG. 5 is a back view of FIG. 1;

FIG. 6 is a front view of FIG. 1;

FIG. 7 is a left side view of FIG. 1; and,

FIG. 8 is a right side view of FIG. 1.

The broken lines in the drawings illustrate portions of the coupling member and form no part of the claimed design.

1 Claim, 6 Drawing Sheets# US D835,976 S
